FIG. 3.

Attorneys

UNITED STATES PATENT OFFICE.

CARL L. JOHNSON, OF ATWATER, MINNESOTA.

ARM GUARD.

Application filed March 14, 1923. Serial No. 625,024.

To all whom it may concern:

Be it known that I, CARL L. JOHNSON, a citizen of the United States, residing at Atwater, in the county of Kandiyohi and 5 State of Minnesota, have invented certain new and useful Improvements in Arm Guards, of which the following is a specification.

This invention relates to a novel arm protecting cuff to be used by persons when cranking internal combustion engines to prevent bodily injury.

The primary object of this invention is the provision of a protecting cuff to be worn 10 upon the arm and over the wrist and upper part of the hand of a person, so that any blows accidentally resulting from an operation, such as the kicking of a crank incident to back fire when starting an internal combustion engine will not result in injury to the arm, wrist or hand of the wearer.

A further object of this invention is the provision of a cuff or piece of armor of the above mentioned character, preferably inherently rigid so that the same may be subjected to very forceful blows without 25 mutilation thereof.

Other objects and advantages of this invention will be apparent during the course 30 of the following detailed description.

In the accompanying drawing, forming a part of this specification, and wherein similar reference characters designate corresponding parts throughout the several views.

Figure 1 is a perspective view of a person about to crank the engine of an automotive vehicle, this person having the improved cuff upon his cranking arm as to obviate injury should the crank be jerked from his 40 hand incident to engine backfire.

Figure 2 is a side elevation of the improved cuff, showing the outer side thereof.

Figure 3 is an opposite side elevation of the improved cuff, showing the inner side 45 thereof.

Figure 4 is a fragmentary cross sectional view, showing the novel protecting construction of the improved cuff.

In the drawing, wherein for the purpose 50 of illustration is shown but the preferred embodiment of this invention, the letter A generally designates the improved protecting cuff, which preferably includes the main cuff portion 10, formed of sheet steel, galvanized metal, or analogous inherently rigid material, the same being rolled to provide a

sleeve which uniformly increases in diameter from its lower end to the upper end thereof. The lower end of the body portion 10 is preferably transversely recessed in concaved manner, so that end lips 12 and 13 extend outwardly at opposite points at the lower end of the cuff body portion 10, which are respectively adapted to overlie the back and forward parts of the wrist and upper hand portion of the wearer to amply protect the same. It is to be noted that the lip 12 which overlies the back of the hand or wrist of the wearer is relatively longer than the opposite lip 13. The extreme lower marginal edge 14 of the body portion 10, is of course attenuated so as not to provide any abrupt surfaces. The upper marginal edge 15 of the body 10 preferably lies in a plane which is at an acute angle to the axis of the cuff 75 A, so that the highest portion 16 of the upper end of the cuff A lies adjacent the back of the elbow of a wearer, and the lowermost portion 17 will lie at the hollow of the elbow of the wearer to permit arm movement 80 during a cranking operation.

At the lower and upper ends of the cuff armor 10, protecting linings 20 and 21 are positioned, which may be of leather or analogous flexible material. These linings 85 are preferably of uniform width about the circumference of the sleeve A, and conform to the contour of the marginal edges of the ends of the body portion 10. They are so positioned that the major widths thereof 90 extend within and are in abutting relation with the inside surfaces of the sleeve armor 10, and are riveted to the latter as by elements 24, so that the minor widths of the protecting linings 20 extend outwardly beyond the outer marginal edges 14 and 15 of the body 10.

The position of the arm guard A upon the arm of a wearer can well be understood from the above description, and from the illustration in Figure 1 of the drawing. Incident to the outwardly extending slightly yieldable protecting linings 20 and 21, the skin and clothing of the wearer is not subject to laceration or tearing, and these linings incident to their external projection at the ends of the sleeve A tend to buff the blows upon the sleeve or guard A. It is of course within the contemplation of the inventor to entirely line the protecting cuff, 110 but an economical construction is that as herein described. In position upon the arm

of a wearer the smaller end of the sleeve A is of course adjacent the wrist of the wearer and the projecting lips 12 and 13 respectively overlie the outer and inner sides of the 5 wrist or upper hand of the wearer. Incident to the fact that the outwardly extending part of the lining 20 is formed according to the contour of the marginal edge 14, the same will naturally conform to the contour 10 of the hand and wrist of the wearer so that a maximum protection is afforded, although not interfering with the free hand movement necessary for a cranking operation.

15 Various changes in the shape, size and arrangement of parts may be made to the form of invention herein shown and described, without departing from the spirit of the invention or scope of the claims.

I claim:

20 1. A protecting cuff of the class described formed of sheet metal and having downwardly extending protecting lips at the lower end adapted to extend over the outer and inner sides of the hand and wrist of a 25 wearer, the outer lip being of greater length than the inner lip.

2. A protecting cuff of the class described formed of rigid metal having outwardly extending protecting lips at an end thereof adapted to extend over the outer and inner sides of the hand and wrist of the wearer 30 for protecting purposes.

3. As a new article of manufacture, a protecting cuff including a rigid body portion

having its lower end provided with inner 35 and outer depending hand and wrist protecting lips, the outer lip being of greater length than the inner lip, and yieldable linings secured in the ends of said body and extending outwardly therefrom, the lower 40 one of said linings having its edges extending parallel to the lower edge of the body and providing oppositely disposed outwardly 45 extending lips thereon adapted to overlie the inner and outer sides of the hand and wrist of a wearer for protection purposes.

4. As a new article of manufacture, a protecting cuff of the class described including a metal protecting casing increasing uniformly in diameter from the lower end thereof toward the upper end thereof, said lower end thereof having a transversely concaved margin to provide outwardly extending protecting lips adapted to extend over in protecting relation at the inner and outer sides 55 of the wrist and hand of a wearer, the upper marginal edge of said casing being disposed substantially in a plane at acute angles with respect to the axis of the cuff, and leather linings riveted to the cuff casing within the 60 same at the ends thereof, said linings having portions which extend outwardly from the outer marginal edges of the ends of said casing portion in conforming relation with the contour of the marginal edges of said 65 casing portion.

CARL L. JOHNSON.
